UNITED STATES PATENT OFFICE.

CHARLES J. CARLSON, OF COKATO, MINNESOTA.

CURRY-COMB AND CLEANER.

SPECIFICATION forming part of Letters Patent No. 461,543, dated October 20, 1891.

Application filed December 27, 1890. Serial No. 375,960. (No model.)

To all whom it may concern:

Be it known that I, CHARLES J. CARLSON, a citizen of the United States, residing at Cokato, in the county of Wright and State of Minnesota, have invented a new and useful Curry-Comb and Cleaner, of which the following is a specification.

The invention relates to improvements in curry-combs and cleaners.

10 The object of the present invention is to provide a simple and inexpensive curry-comb and means for readily and effectively cleaning the same.

The invention consists in the construction and novel combination and arrangement of parts hereinafter fully described, illustrated in the accompanying drawings, and pointed out in the claims hereto appended.

In the drawings, Figure 1 is a perspective view of a curry-comb embodying the invention. Fig. 2 is a reverse plan view, the cleaner being swung back. Fig. 3 is a longitudinal sectional view. Fig. 4 is a transverse sectional view.

25 Referring to the accompanying drawings, 1 designates a curry-comb frame approximately rectangular and constructed of suitable metal and provided with an integral shank 2, to which is secured a handle 3. The 30 rectangular frame 1, to which teeth-plates 4 are secured, consists of side bars 5, end bars 6, and an intermediate cross-bar 7, which is provided on its lower face with integral rivets 8, passing through the plates 4 and securing the same at points intermediate their 35 ends. The plates are of the usual construction and are provided at their ends with flanges 9, which are arranged in slots 10 of the end bars 6 and are bent inward over the 40 same, thereby securing the ends of the plates to the frame, and the end bars are recessed on the inner side of the frame and rounded to receive the flanges 9. One end of the frame is provided with a series of hooks or 45 open eyes 11, formed integral with the adjacent end bar and adapted to hinge to the curry-comb a cleaner 12, composed of a series of longitudinal loops, each having one end engaging one of the open eyes or hooks

11, and when the comb is in use the loops 50 are arranged between the toothed flanges of the plates 4, and after using, the wire frame is swung outward to clean the comb, and it will readily be seen that the wire cleaner 12 can be readily operated and will not be rendered inoperative by a slight bending of the flanges of the plates 4. The cleaner 12 consists of a wire frame 13, which is bent to form end loops 14, and intermediate separate wire loops 15 are arranged between the end 60 loops 14 and secured to the frame and are provided at their ends with eyes 16, which engage the transverse end wire 17 of the frame 13, and the sides of the loops are held in their proper positions by spacing-sleeves 65 18, arranged upon the transverse wire 17. The transverse wire is bent intermediate its ends to form a loop or lip 19, which engages recesses 20 of one of the end bars 6 and secures the cleaner to the comb when the latter 70 is in use.

It will be seen that the curry-comb and cleaner are simple and inexpensive and effective, and that the cleaner is not rendered inoperative by the slight bending of the 75 flanges of the teeth-plates.

From the foregoing description and the accompanying drawings the construction, operation, and advantages of the invention will readily be understood.

80 What I claim is—

1. In a curry-comb, the combination of the rectangular frame comprising the side bars, the end bars provided with slots and with recesses on the inner side of the frame, the cross-bar having integral rivets on its lower face, and the teeth-plates 4, secured to the frame intermediate of their ends by the rivets of the cross-bar and provided at their ends with flanges engaging the slots of the end bars and arranged flush within the recesses, substantially as described.

2. In a curry-comb, the combination of the frame provided at one end with open eyes or hooks, the teeth-plates secured to the frame, the cleaner consisting of a frame constructed of a single piece of wire bent to form end loops 14, a transverse bar connecting the loops

and provided with the bend forming the lip 17 to engage the curry-comb frame, the intermediate separate loops provided with eyes arranged on the transverse bar 17, and the spacing-sleeves arranged on the bar 17 and separating the sides of the loops, substantially as described.

In testimony that I claim the foregoing as my own I have hereto affixed my signature in presence of two witnesses.

CHARLES J. CARLSON.
